REFLECTOR

Jack F. Brady, Summit, and Michael Melack, Berkeley Heights, N.J., assignors to Elastic Stop Nut Corporation of America, Union, N.J., a corporation of New Jersey

Filed Mar. 22, 1963, Ser. No. 74,088

Term of patent 14 years

(Cl. D72—1)

T 1 Q-1.

T 1 Q-2.

FIGURE 1 is a front view in elevation of a reflector showing our new design; and

FIGURE 2 is a sectional view taken along the line 2—2 of FIGURE 1.

The characteristic features of our design reside in the combination of the recessed relationship of the reflector member with respect to the bezel member and the spaced relationship between the perimeter of the reflector member and the adjacent, concentric periphery of the bezel member as best illustrated in FIGURE 2 and the central aperture through the reflector member and the bezel member, as shown.

We claim:

The ornamental design for a reflector, as shown and described.
